United States Patent Office

Des. 188,630
Patented Aug. 16, 1960

188,630

DISPENSING BOTTLE

Gerhard Neuhaus, Dusseldorf, Germany, assignor to Lingner-Werke G.m.b.H., Dusseldorf, Germany, a corporation

Filed Oct. 5, 1959, Ser. No. 57,812

Term of patent 14 years

(Cl. D58—6)

FIG.1

Fig. 1 is a side elevational view of a dispensing bottle, showing my new design.

Fig. 2 is a top view thereof.

Fig. 3 is a front elevational view thereof.

The side not shown is the same as the side shown.

I claim:

The ornamental design for a dispensing bottle, as shown and described.
